J. G. THEOBALD

CIGARETTE HOLDER

Filed Jan. 15, 1923

Inventor
Jean George Theobald
By Joseph A. Miller
Attorney

Patented Jan. 8, 1924.

UNITED STATES PATENT OFFICE.

JEAN G. THEOBALD, OF ATTLEBORO, MASSACHUSETTS.

CIGARETTE HOLDER.

Application filed January 15, 1923. Serial No. 612,659.

To all whom it may concern:

Be it known that I, JEAN GEORGE THEOBALD, a citizen of the United States, residing at Attleboro, in the county of Bristol and 5 State of Massachusetts, have invented new and useful Improvements in Cigarette Holders, of which the following is a specification.

This invention relates to certain new and 10 useful improvements in cigarette holders and the primary object thereof is to provide a holder which can be easily collapsed or taken apart and the parts nested so as to enable same to be more easily carried in the 15 pocket of the user, or otherwise carried, and at the same time to prevent escape of the odors or contact of the parts with the pocket or other carrying means.

Still further the invention aims to provide 20 a cigarette holder in which the parts can be easily and quickly cleaned and wherein same are of simple and economical construction.

The invention has still further and other 25 objects which will be later set forth and manifested in the course of the following description.

In the drawings:

Figure 1, is an elevation of the parts in 30 their housed or collapsed position;

Figure 2, is a longitudinal sectional view 35 with the parts in operative position;

Figure 3, is a like view of one of the end caps, and

Figure 4, is a section on line 4-4 of 40 Figure 2.

In proceeding in accordance with the present invention, a tubular body 1 is employed preferably of ovaloid cross section, 45 as depicted in Figure 4. The body has open ends and affords a combined holder proper for the cigarette and a casing or housing for the mouthpiece 2. The mouthpiece may be of any desired construction and has a cap 3 50 attached to its inner end, the cap being formed with a bead 4 intermediate its ends to engage the end of the body 1. The cap has an end wall 5 formed with a hollow knob 6, the knob having a central perforation 7 and radial perforations 8, the several 55 perforations affording ports or openings through which the smoke from the cigarette is drawn into and through the mouth piece. As shown in Figure 2 the end wall 5 is bowed outwardly from the adjacent end of the mouthpiece 2 so as to form a chamber 9

affording means to provide free drawing of the smoke from the cigarette. A similar cap 10 having a bead 11 is removably connected to the opposite end of the tubular body 1, the two caps 3 and 10 being of like construction or formation so as to provide a symmetrical appearance when the parts are in the housed or collapsed position illustrated in Figure 1 of the drawing, and to 60 also afford free drawing of the cigarette when the parts are in the position of Figure 2.

In operation, with the parts illustrated in the housed position of Figure 1 it will be 70 seen that the cap 3 is in a reverse position to that illustrated in Figure 2, the mouth piece 2 in Figure 1 being disposed on the interior of the body 1, and the cap 10 being applied to the opposite end of the body 1. In order to assemble the parts for use, the cap 10 is removed and also the cap 3, each being then reversed and inserted into the opposite ends of the body 1 as shown in Figure 2. 75 The cap 10, in the latter instance then serves as a socket or holder to receive the end of the cigarette, while in the position of the parts in Figure 1, the cap 10 serves to close the body, the latter containing the mouth-piece. The cap 10 if desired can be removed from the Figure 2 and the cigarette held directly by the body 1. With the parts 80 in the position of Figure 1 it will be seen that the mouth piece is in the body and the caps 3 and 10 serve to close the ends of the 85 body so as to prevent the escape of tobacco odors from either the body or the mouth piece. The parts can thus be carried either in the pocket or in a bag or otherwise, without any possibility of the tobacco odors being 90 communicated to the pocket or a bag or the like, and in addition the mouth piece is prevented from contacting with the pocket or other carrying media.

Having thus described my invention, 95 what I claim as new and desire to secure by Letters Patent is:-

1. In a collapsible cigarette holder, a tubular body open at each end and affording a holder for the cigarette and a housing for the mouthpiece, a cap on the inner end of the mouthpiece having a bead intermediate its ends and having either of the latter receivable in the body, said cap having an end wall and a hollow knob extending 105 out from the end wall, the knob being formed with a central opening and with 110

radial openings, and a cap of a similar construction having each of the ends thereof, receivable in the body for closing the opposite end of the body in one position and in a reversed position affording a holder proper for the cigarette.

2. In a collapsible cigarette holder, a tubular body open at each end and affording a holder for the cigarette and a housing for the mouthpiece, a mouthpiece, a cap on the inner end of the mouthpiece having either of its ends receivable in the body, and a reversible cap for closing the opposite end of the body and for providing a holder proper for the cigarette.

3. In a cigarette holder, a body having open ends, a mouthpiece, means to removably connect the mouthpiece to one end of the body and with the latter providing a holder for the cigarette, said means being formed to connect the mouthpiece to the body and to house the mouthpiece in the body, and means for closing the opposite end of the body and for affording a holder proper for the cigarette.

4. In a cigarette holder, a tubular body, open at each end, a mouthpiece, a cap fitted over one end of mouthpiece and having a perforated outer end wall, stop means on the cap between its ends, said cap in one position having one end engaging in the body to hold the mouthpiece therein and in a second

position having its opposite end engaging in the body to hold the mouth piece projecting out from the body so as to enable the latter to serve as a holder proper for the cigarette, and means to close the opposite end of the body.

5. In a cigarette holder, a body, a mouthpiece, means to connect the mouthpiece to the body so as to be housed by the latter in one position and to project outwardly therefrom in a second position, and combined body closing and cigarette holding means formed for connection with the body to close the latter in one position and in a second position to hold the cigarette.

6. In a cigarette holder, a body, a mouthpiece, and a pair of caps, one of which is connected to the mouthpiece, said caps being reversibly received in the body whereby to house the mouthpiece in the body with the other cap closing the body in one position of the parts and in a second position to hold the mouthpiece projecting outwardly from the body and with the other cap forming a holder proper for the cigarette.

In testimony whereof I have signed my name to this specification in the presence of two subscribing witnesses.

JEAN G. THEOBALD.
